ATTORNEYS.

UNITED STATES PATENT OFFICE.

JOHN A. BOYCE, OF CHICAGO, ILLINOIS.

PRINTING AND FOLDING MACHINE.

1,353,799.

Specification of Letters Patent. Patented Sept. 21, 1920.

Application filed October 17, 1913, Serial No. 796,080. Renewed November 17, 1919. Serial No. 338,524.

To all whom it may concern:

Be it known that I, JOHN A. BOYCE, a citizen of the United States, residing at Chicago, in the county of Cook and State of Illinois, have invented new and useful Improvements in Printing and Folding Machines, of which the following is a specification.

My invention relates to improvements in
machines for printing and folding papers
and relates more particularly to that class
of machinery designated as "rotary web-
printing, folding, and delivering machines".

15 A primary object of my invention is to reduce the number of stereotype plates employed, by providing a single set of plates on each printing cylinder, whereon have formerly been used duplicate plates, and, in lieu of a second set of plates, to provide

20 a second impression roller, whereby to accomplish the novel and effective result of perfecting the web by negotiating two like impressions thereon, one following the other with usual margins intervening, in each

25 complete revolution of the plate cylinder, resulting in the increased efficiency of the machine.

Another object is to provide means for relieving the pressure between the plate and impression cylinders when the press is standing idle, without the necessity of removing the stereotype plates.

A further object is to provide an effective forwarding device controlling the web and relieving the strain thereon, which device will make it possible to thread the web into the printing and folding machine without the necessity of having any of the plates in place on the cylinders.

40 It is a well known fact that form rollers, covered with composition, are very expensive and are easily worn out. In order to render my printing machine more economical and efficient, I provide means whereby 45 these rollers may run on a smooth surface for one-half of each revolution of the plate cylinders, thus effectively reducing the wear on the rollers.

A still further result which I desire to attain in my invention is to make it possible to use but a single ink fountain for each plate cylinder by the adoption of a novel and effective method of ink distribution.

With the above and other objects in view,
55 my invention consists of the novel construction
and arrangement of the several ele-

ments of my printing and folding machine, which features will be hereinafter fully described, illustrated in the accompanying drawings, and pointed out by and in the appended claims. 60

Reference may be had to prior patents granted to me bearing the following designation, #963,203, patented July 5, 1910 and 924,310 patented June 8, 1909, wherein several of the features embodied in my present invention are partially disclosed, but in my present disclosure substantial improvements thereon will be pointed out and illustrated in the drawings. 70

In the drawings; wherein like reference characters refer to like or corresponding parts throughout the several views, it has been deemed expedient to employ conventional and diagrammatical means of illustration where possible, since the elements, when not otherwise shown in detail, are to be understood to be of the usual, or any approved construction, well known in the art. 75

Figure 1 is a diagrammatical side elevation of my improved printing and folding machine; Fig. 2 is a perspective outline of the driving mechanism; Fig. 3 is a detail side elevation of one of the web tensioning members; Fig. 4 is a detail rear elevation of one of the web tensioning members; Fig. 5 is a diagram showing the driving gears and method of applying the drive to the several printing elements; Fig. 6 is an end elevation of the ink distribution element, showing my improved method of adjustment; Fig. 7 is an elevation of the opposite end of the ink distribution elements; Fig. 8 is a diagrammatical illustration of the drive between ink fountains; Figs. 9 and 10 are perspective views of the two methods of providing adjustment for the impression cylinders; Fig. 11 is a perspective view, illustrating the form rollers and the method employed for mounting them in their working position; Figs. 12 and 13 are detail elevations of the supporting arm upon which I mount my form rollers; Fig. 14 is a perspective view of one of the impression cylinders showing means for attaching the 100

linders, showing blanket and muslin covering; Fig. 15 is an end elevation of the same impression roller, illustrating the same device; Fig. 16 is an end elevation of one of the pivoted mounting devices for a web-directing roller; Fig. 17 is a perspective view of one of the web forwarding cylinders showing the means

employed for attaching and tightening the packing; Fig. 18 is a sectional view through one of the web forwarding cylinders; Fig. 19 is a fragmentary end view of one of the 5 web forwarding cylinders; Fig. 20 is an elevation of another of the web forwarding cylinders showing another means of attaching the packing; Fig. 21 is a fragmentary end elevation of the same cylinder; Fig. 22 10 is a perspective view of the two web forwarding cylinders and the method of driving them; Fig. 23 is a side elevation of one of the flexible mountings for a web directing roller; Fig. 24 is a front elevation of 15 the paper folding mechanism; Fig. 25 is a longitudinal sectional view of the folding cylinder; Fig. 26 is a detail perspective view of one of the web carrying means; Fig. 27 is a diagram of a run of web when using a 20 full complement of plates; Fig. 28 is a run of web when the web forwarding cylinders are not in use and the plate cylinders equipped with half a complement of plates; and Fig. 29 is an end elevation of the folding 25 cylinders.

In describing the printing press of my invention it is not thought necessary to go into detail regarding that portion of the apparatus which is known to be old and which 30 I do not attempt to cover by Letters Patent. I therefore limit the detail description, in so far as possible, to the portion of the device which I claim as new. I have also illustrated a three-deck machine, but where- 35 in the three decks are similar, I propose to describe but one deck, it being understood that the other decks are similar in arrangement and operation.

The supporting frame work is designated 40 in general by the reference letter A, and which follows the usual accepted design. The several cylinder members are mounted thereon, bearings being provided therefor in the usual manner. I have, however, pro- 45 vided a novel arrangement of the several elements of my machine with reference to the central vertical frame columns A' by positioning the plate cylinders 7 and 10 at a sufficient distance from the column A' to 50 allow easy access thereto in applying and removing plates. By mounting my relatively small impression cylinders 6 and 15 on a line with and between the plate cylinders, I have also economized the space and 55 rendered my plate cylinders more accessible. By providing the vertical drive shaft 24, (see Fig. 5) on one side of the machine, and the driving gears on the opposite side, I am enabled to have the shaft side of my 60 press relatively free from mechanism to obstruct the access to the plate and other cylinders.

By reference to Fig. 11, it will be seen 65 that I have provided the plate cylinders for normal operation with only a half a com-

plement of stereotype plates, the other half of the cylinders being provided with a smooth surface plate 12, which is only slightly lower than the type on the stereotype plate. Smooth surface 12 may be 70 formed on the plate cylinder, but it is preferable to provide a removable plate, as will hereinafter appear. The plate cylinders 7 and 10 are in circumference equal to the length of two plates plus margins, the columns of the stereotype plate running circumferential thereof. It will be understood 75 that the stereotype plate on one cylinder is adapted to perfect one side of the web, while the other side of the web is perfected 80 by the other plate cylinder.

By reference to Fig. 1, it will be seen that the web is introduced to the press in a novel manner. It was prior practice to introduce the web from a roll of paper such as 1 to 85 pass between the impression cylinder and the plate cylinder. I employ a web forwarding device consisting of a set of web-directing rollers 2, 3 and 4 which direct the web between the web forwarding rollers 13 and 14, to a roller 5 and thence downward between the impression cylinder 6 and the plate cylinder 7. At this point the web is perfected by the plate cylinder 7 and passes under rollers 8 and 8' and upward between 90 plate cylinder 7 and the second impression cylinder 9. The travel of the web is so predetermined that the second impression given to the web by its second contact with the stereotype plate 11 (see Fig. 11) will be 95 properly spaced thereon, that is to say, the two impressions will be positioned one after the other on the web, double margins intervening. The web is then turned and directed by rollers 17 and 18 to pass over impression cylinder 15 and downward between that impression cylinder and the plate cylinder 10, and under rollers 19 and 20 to pass upward between the impression cylinder 16 and plate cylinder 10, where the web 110 is perfected on the opposite side.

I have provided a novel means for driving the several rotating parts of my invention, which consists of the arrangement shown in Figs. 2 and 5. Numeral 21 designates a horizontal shaft which extends crosswise of the machine, and is positioned preferably beneath the machine. Shaft 21 is provided with a bevel gear 22 which is positioned just outside of and below one of 120 the side walls of the frame and which is adapted to mesh with a second bevel gear 23 carried by a perpendicular shaft 24. Shaft 24 is provided with other spaced apart bevel gears designated as 25 and which 125 may be termed deck-driving gears. Gears 25 are adapted to mesh with gears 26, which gears are mounted on the shaft 38 of the forwarding roller 13. Shaft 38 is provided at its opposite end, and on the opposite side 130

of the machine, with spur gear 40 adapted to mesh with spur gears 27 and 28 suitably located on either side thereof on the same side of the machine. Spur gear 27 is mounted on shaft 39, upon which shaft is mounted the second web forwarding roller 14. Spur gear 28 is adapted to mesh with a spur gear 29 carried on shaft 30, upon which shaft 30 is also mounted the plate cylinder 7. Meshing with gear 29 and preferably located in line with shaft 30 are the two impression cylinder gears designated as 31 and 32 mounted respectively on shafts 41 and 42. The other plate cylinder gear 29' mounted on shaft 30', is driven from spur gear 27 through the medium of spur gear 35. Impression cylinder gears 32' and 31' are driven by the plate cylinder gear 29'. Fig. 22 illustrates my method of throwing any one of the decks out of operation. Gear 40 is slidably keyed to shaft 38 upon which is mounted forwarding cylinder 13. By sliding gear 40 outward on shaft 38, the entire deck will be thrown out of operation.

In my present invention wherein is provided for normal operation only half a complement of plates, I provide but a single ink fountain to each plate cylinder. I employ in conjunction with the ink fountain 50, ink roller 52, ductor roller 53, ink drum 54, vibrating rollers 57, 58 and 59, and iron rider 60, through the medium of which the ink is carried from the fountain and placed on the composition form rollers 61. Rollers 61, of which there are two, (see Fig. 11), are mounted upon supporting arms 78, which arms are carried by brackets 79 attached to the frame. Rollers 61 are adapted to ink plates carried by the plate cylinder. A second pair of form rollers designated as 62 are supported by a second set of arms 78 and are positioned below the plate cylinder 7 being adapted to travel upon the plates carried by the plate cylinder. Means which will be hereinafter set forth are adapted to raise and lower the form roller members 61 and 62 to accommodate the two previously mentioned heights of plates applied to the plate cylinder. It will be readily seen that the ink placed on the smooth plate 12 carried on half of the surface of the plate cylinder by the rollers 61 will be taken up by the second set of rollers 62 and placed upon the stereotype plate during the following half revolution of the cylinder.

I employ the ordinary type of ink roller 52 having a cam on one end thereof by which the ductor roller 53 is actuated into contact with the ink drum 54, but I provide a new and efficient method of adjustment therefor, which is adapted to work in conjunction therewith. (See Figs. 6 and 7.) A cam designated as 80 is attached to the ink roller shaft 51 at the opposite end from cam 79. In addition to the usual supporting

arms 77 of the ductor roller 53, I provide an adjustment arm 76 which is fixed to shaft 75 to which arms 77 are attached. A roller 81 is carried by arm 76, which roller is adapted to run on cam 80. By any suitable method, roller 81 may be movably attached to the outer end of arm 76, as by being adjustably carried in a slot therein, whereby the roller may be shifted into actuated relation with cam 80. Cam 80 is positioned to actuate roller 81, and, thereby, arm 76 and ink ductor roller 53, away from the ink roller 52, at the point in the revolution of the ink roller just before the cam 79 is in position to likewise actuate the ductor roller. By this means, the length of time in which the ductor 53 is in contact with ink roller 52 will be diminished, and, consequently the amount of ink taken up by the ductor roller 53 will be correspondingly decreased.

By reference to Figs. 9 and 10, the method of providing adjustment for the impression cylinders will be readily understood. For impression cylinder 9 I have adopted the arrangement shown in Fig. 9, for which I provide a rectangular opening 63 in the frame, and into which is inserted sliding block 64, which provides the bearing for shaft 41. An adjusting bolt 66 having a head 83 abutting against one side of block 64 passes through a fixed standard 82 formed in opening 63, and a nut and lock nut 69 are carried by said adjusting bolt on the opposite side of the standard. A nut 70 is carried on bolt 66 between head 83 and standard 82, and a bifurcated key 65 straddles the adjusting bolt 66 between the nut 70 and the standard 82. When quick adjustment is required, key 65 may be removed and the impression roller bearing 95 shifted in position. To provide movement of bearing 64 in the opposite direction, I provide a wedge 67 having a tapered face adapted to slide on a similarly tapered face carried by bearing block 64, and an adjusting screw 68. By forcing wedge 67 downward between the tapered face of block 64 and the wall of opening 63 by means of the adjusting screw 68, movement of the block may be readily accomplished.

The arrangement of the several elements of my machine makes it expedient to employ such means as are illustrated in Fig. 10 for the adjustment of the bearing for impression roller 6. A rectangular opening 74 provides a slide way for bearing block 71, in which shaft 42 rotates. Both of the end faces of block 71 are tapered, and similarly tapered wedges 72 are provided, which wedges are adapted to be actuated upward and downward between the walls of opening 74 and the tapered faces of block 71, by set screws 73, thereby providing adjustment of position for the impression roller.

Improved means for driving the ink rollers

is clearly illustrated in Fig. 8, by reference to which it will be seen that bevel gear 45, carried by shaft 30 of the plate cylinder, drives a relatively larger bevel gear 46 keyed 5 to the ink roller drive shaft 85. Shaft 85 extends at right angles to shaft 30 and carries a bevel gear 86 on its opposite end, which bevel gear drives a second relatively larger gear 87 mounted on the ink roller shaft 51, 10 resulting in a continuous revolution at a reduced speed of the ink roller 52 in fountain 50.

The means employed for vibrating the several ink distributing rollers 59, 58 and 57 is 15 well known to the art, and is accomplished by eccentrics 88 carried on shaft 85, but I have embodied novel improvements therein. Previously a vibrating arm such as 196 has been employed for each roller to be vibrated, 20 and the eccentrics 88 were fixed to their shaft to actuate the rollers at different points in the revolution of their drive shaft. This drive was accomplished by special gearing on the opposite side of the printing machine 25 and was complicated and difficult of access. I propose to actuate my rollers 57, 58 and 59 at the same time by arranging eccentrics 88 on the ink roller drive shaft 85 to so operate, and to provide an extension arm 197, attached 30 to arm 196, to vibrate roller 58.

The means which I employ for raising and lowering the form rollers 61 and 62 is shown in perspective in Fig. 11. The supporting arms are shown in greater detail in Figs. 12 35 and 13. Arms 78 are anchored by means of brackets 79 to the frame, and positioned so that the shafts of the form rollers 61 and 62 may be carried in the bearing slots 90 provided in bearing brackets 93, key 91 being 40 adapted to secure the shafts in place. Bearing brackets 93 are slideable upon their respective arms 78, and are held in place by nuts 94 on either side of the L-shaped projection 96 through which adjusting stud 95 extends. Adjusting stud 95 is formed integral 45 with arm 78 and is a continuation thereof. The opposite end of arm 78 is bifurcated and a roller 97 is pivoted between the bifurcations. Intermediate the lugs 98 of bracket 50 79, a coil spring 99 is carried by arm 78. Spring 99 is seated at its outer end against one of the lugs 98, and at the other end against pin 100 carried by arm 78. Rollers 97 on the inner ends of arm 78 are adapted 55 to roll upon the revolving shaft 30 of the plate cylinder 7. In order to raise the form rollers carried by arms 78 to accommodate the two heights of plate carried by cylinder 7, I provide a raised surface 106 on shaft 30 60 in the path of travel of the rollers. The raised surface 106 corresponds in height to the difference in height of the stereotype plate 11 and the smooth surface plate 12 on cylinder 7, and is properly positioned to raise the 65 rollers when they are to travel on the stereo-

type or thicker plate 11. An adjusting eccentric 101 is pivoted by screw 102 to arm 78, and by rotating eccentric 101 by means of key 103, the shifting of position of bearing brackets 93 may be effected, the eccentric being adapted to contact with stationary bracket 79 in which arm 78 is slideable. Notches 105 are adapted to receive pin 104 at the several predetermined positions of adjustment. Adjusting eccentric 101 makes it possible to 70 raise the rollers 97 entirely out of contact when the machine is at rest, or, when it is desired to use a full complement of stereotype plates when increasing the capacity of the machine, the rollers may be adjusted to 75 operate in the position where they will just touch the plates.

Figs. 14 and 15 illustrate my improved method of attaching the blanket and muslin to the impression cylinders. I provide a 80 longitudinally extending slot 106 through the outer walls of the impression cylinder, one edge of said slot being provided with a series of pins 107 extending therefrom. The blanket and muslin covering therefor are 85 caught in the pins 107 and drawn around the cylinder and threaded into the slot 106, which slot is preferably only wide enough to receive the blanket and muslin cover. The free end of the blanket is then threaded 90 into the longitudinal slot 108 carried by roller 109 and the roller revolved about its axis in the impression cylinder heads, and the blanket thus rolled thereon and drawn tight about the impression cylinder. Likewise the free end of the muslin is threaded 95 into slot 110 of the roller 111 and drawn tightly in place. Dogs 112 coat with cog wheels 113 to prevent the unrolling of the rollers 109 and 111.

Means for tightening the packing about the forwarding roller 13 is shown in Figs. 17, 18 and 19. Cylinder 13 is provided with a relatively narrow longitudinal slot 112 communicating with a preferably rectangular longitudinal opening 113 carried in the cylinder. A square sectioned rod 114 extends longitudinally of the opening 113 and is provided with a bearing in the heads of the cylinder in which it may be rotated. 118 The packing material for the cylinder is fashioned to form a substantially cylindrical cover, and the seam is caught in pins 115 carried by rod 114, whereby the packing may be wound about rod 114 and drawn 120 tightly in place. Cog 116, and coacting dog 117 prevent reverse motion of the rod 114.

For the tightening of the packing about forwarding roller 14, I provide the means shown in Figs. 20 and 21. Two relatively 125 wide slots 118 are formed longitudinally of cylinder 14, preferably 180 degrees apart and each extend from opposite ends to points adjacent the center of the length of the cylinder. A square rod 119 is carried 130

longitudinally of each of the slots, and pins 120 are provided on one of the lateral walls of the slot. Two strips of packing material are required, each in width equal to one-half of the length of cylinder 14. One end of the packing strips is caught by pins 120 in slots 118 and the other free end carried around the cylinder, threaded into slot 118 and caught by pins 121 carried by rods 119. The rods may then be rotated to tighten the packing about the cylinder. Means similar to that shown in Fig. 19 may be employed to prevent reversed motion of rods 119.

A paper tensioning device such as is shown in Figs. 3 and 4 are employed, numeral 123 designating a bearing drum adapted to receive shaft 122 of the paper rolls 1. Clamps 124 and 125, adapted to be adjusted by hand screw 126, provide tension about the bearing drum 123 into which shaft 122 is keyed. Longitudinal movement of the paper rolls is secured by means of feed screw 127, by which block 128 may be actuated in and out, and with it the drum 123, and paper roll 1, block 128 fitting into a groove 129 therefor in drum 123.

I have provided the means shown in Fig. 23 for flexibly mounting the ends of roller 2 whereby the web in passing from the paper rolls 1 may be held tight and yet allow roller 2 to shift slightly at either end upon the event of unevenness in the paper roll. Numeral 190 designates a bracket, mounted to the main frame A in any suitable manner, 35 and having slidably mounted therein, a pin 191. Pin 191 is preferably placed to slide back and forth in line with the pull on the web, and coil springs 192 and 193 are carried about said pin on either side of the bracket 40 190. On one end of pin 190 is mounted the bearing fixture 194 in which the shaft of roller 2 is mounted to rotate. A fixed collar or head 195 is carried by the opposite end of pin 191, and forms a seat for the spring 193. 45 It will be seen that such an arrangement provides flexibility in both directions and will readily compensate for any unevenness in the pull on the web, thus preventing the breaking of the web caused by such unevenness.

After the several webs have passed through the process of being perfected on both sides, they are collected by being directed about rollers 170 to pass over roller 55 136 leading to the folding device which is illustrated in Fig. 24. The shaft on which roller 136 is mounted is rotated by a bevel gear 135 which is actuated by a bevel gear 134 mounted on vertical shaft 124. Shaft 134 is driven by shaft 127 through the medium of bevel gear 126 on shaft 127 and bevel gear 125 on shaft 124. Shaft 127 is actuated from the main drive shaft 21 through the medium of bevel gears 133, 132, 60 shaft 131 and bevel gears 129 and 128. This

drive may be readily understood by reference to Fig. 2. Parallel to and above roller 136 is a shaft 137 provided with fingers 138 on the end of which fingers are mounted rollers 139 for the purpose of providing tension at this point in the run. Numeral 140 designates a former which is of the ordinary type and which folds the webs lengthwise between the pages. The perfected webs pass downward therefrom between rollers 142 and 141, which rollers are geared to revolve in opposite directions and thus to forward the folded webs downward between the folding cylinders 143 and 144. Cylinder 144 is provided with a knife 173 which is adapted to engage in slots 172 carried by cylinder 143 each full revolution of cylinder 144 and each half revolution of cylinder 143. This arrangement is shown in detail in Fig. 29.

I provide my folding cylinder, as shown in Figs. 25, 26 and 29, with the usual set of forwarding pins 163 which are adapted to protrude from the cylinder through slots 164. Pins 163 are mounted on arms 162, which arms are carried by shafts 161 mounted longitudinally of the cylinder at substantially 180 degrees apart and which shafts are actuated by means of arms 160 outside of the cylinder, which arms are provided with rollers 167 adapted to ride on a stationary cam 159 provided also without the cylinder. Cam 159 is carried by a stationary drum member 157, of which there are two, the other being designated as 157' and positioned at the opposite end of cylinder 143. Drum members 157 and 157' provide channels 158 and 158' in which spur pinions 156 mounted on the ends of the shafts carrying the folding blades 165 may travel. Folding blades 165 are also mounted within the folding cylinder 143, longitudinally thereof, and are adapted to revolve in slots 168 provided therefor. At predetermined points in the channel 158 are 100 teeth adapted to mesh with the spurs 156 to revolve the folding blade.

It will be seen that as the folded web passes between the cylinders 143 and 144 pins 163 will engage the edge of the web 115 and carry it downward with the revolution of folding cylinders 143 one-half of the distance around the folding cylinder. At this point, pins 163 will be released by action of arm 160 and its roller 167 upon cam 159. 120 At this point, also, the folding blade 165 will have reached a position just above and between rollers 151 and 152, when it will be revolved in slot 168, through the actuation thereof by spur pinions 156, and one of the sharp edges thereof turned downward between rollers 151 and 152. Knife 173 of cylinder 144 will have reached its position to register with slot 172 of cylinder 143, 125 and the paper will be severed from the web. 130

Revolving rollers 151 and 152, revolving in opposite directions, will draw the paper downward between them depositing the folded paper, upon the delivering device 5 150, which, in turn, will deliver the paper to the moving tapes actuated by rollers 155 and 154 in a well known manner.

The foregoing folding device is clearly pointed out in my prior Patents #974,231 10 and 900,259 and, since reference may be had thereto, it is not thought necessary to describe the previous disclosure in detail.

Folding cylinder 143 is driven through the medium of the chain of spur gears 148, 15 149, 175 and 130 from shaft 131. Rollers 151 and 152 may be driven by gear 148. The delivering device shaft 150 and the rollers 155 and 154 may be driven by any 20 suitable manner which is not new and which is well known in the art.

It will be found advantageous, in increasing the capacity of my printing machine, to print with a full complement of plates on each of the plate cylinders 7 and 10. 25 Fig. 27 illustrates a run in which the cylinders are thus provided with two sets of stereotype plates, the columns extending circumferentially of the cylinder. The web is passed between the forwarding cylinders 30 13 and 14 downward around roller 5 and over and between impression cylinder 6 and plate cylinder 7. The web is then passed downward around roller 8 and upward passing down between impression cylinder 35 15 and plate cylinder 10, thence under rollers 19, 20, and 170 to the folding device. When this run is used the lower set of form rollers 62 and 62' are thrown out of commission, by shifting the position of those 40 rollers by the actuation of cam 101 carried by hanger arm 78 to the dotted line position shown in Fig. 13. Impression cylinders 9 and 16 are also thrown out of commission by means of the adjusting device shown in 45 Fig. 9.

In accomplishing the foregoing, it will be necessary to collect below the former. The method therefore is clearly disclosed in my former Patent #974,231 granted Nov. 50 1, 1910, and reference may be had thereto, or any other approved construction may be employed.

I have provided a means for omitting the forwarding cylinders 13 and 14 out of 55 the run of web when it is so desired, by means of the run shown in Fig. 28. Forwarding cylinder 13, which may be supported by bearings 200 carried on brackets 201 supported on each side of the machine 60 by central columns A', is laterally adjustable with respect to the other forwarding roller 14. Bearing 200 is slidable on bracket 201, a screw adjustment 203 being provided to accomplish the movement thereof. 65 Through this means cylinder 13 may be

withdrawn from contact with the web. The web is passed under roller 5 thence over impression cylinder 15 and between that impression cylinder and plate cylinder 10, upward from the impression cylinder 15 70 and downward between impression cylinder 6 and plate cylinder 7, under rollers 8 and 8', and upward between impression cylinder 9 and plate cylinder 7, then downward from impression cylinder 9 passing under rollers 75 17, 18 and 20 and upward between impression cylinder 16 and plate cylinder 10. It will be understood that in this run the plate cylinders are provided with but a half a complement of plates, that is one stereotype 80 plate and one smooth plate of less thickness, and that all of the impression cylinders and form rollers are in operation. In this run it is possible to provide tension to the web at all times, as the web will be in contact at 85 some point during the entire run.

In order to accomplish the foregoing result, it is necessary to provide the adjustment for web directing roller 20 which is shown in Fig. 16. Roller 20 is mounted 90 upon arms 185 which arms are pivoted at point 186 to a pivoting plate 187 which may be mounted upon the frame of the printing machine in any desirable manner. Arms 185 are provided with extensions outside of pivoting point 186 which extensions may carry an arcuate slot 188 through which an adjusting bolt 189 may extend. Adjusting bolt 189 is carried by pivoting plate 187 and roller 20 may be swung about pivoting 100 point 186 and fixed at any point in the slot 188 by means of the adjusting bolt.

The guiding rollers 8, 8', 17, 18, 19, 20 and 170 are similarly made adjustable so that the proper length of web will be 105 taken up.

By means of the combinations attainable upon my press I am able to obtain a wide variation in capacity. By providing the plate cylinders on two decks of my machine 110 with a half a complement of plates two pages wide, and the third deck with a half a complement of plates only one page wide, I am able to produce ten pages. By throwing one of the decks out of commission entirely, and providing the plate cylinders of the two remaining decks with half a complement of plates two pages wide, eight 115 pages will be produced. By providing the plate cylinders of all three decks with half a complement of plates two pages wide, twelve pages may be perfected. A sixteen-page product may be attained by providing the plate cylinders of two decks with a full complement of plates, two-page wide, and 120 throwing the other deck entirely out of commission. In this run it will be necessary to thread the web as is shown in Fig. 27. For a twenty-page product two decks 125 may be provided with a full complement of 130

plates two pages wide, and one deck with a full complement of plates using a half width web thereon. For a twenty-four-page paper, the three decks may be equipped with 5 a full complement of plates two pages wide. It will be understood that in all of these combinations all of the decks, when in operation, are run at full speed.

From the foregoing description, it will 10 be apparent that the printing machine of my invention comprises many new and useful improvements, and, while I have herein described and illustrated the preferred embodiment thereof, I do not wish to be limited thereto, except for such limitations as the 15 claims may import, as it is obvious that the details of construction and arrangement and combination of the several elements may be varied in many ways.

Having thus described my invention, what 20 I claim is:—

1. The combination with a plurality of plate cylinders each adapted to perfect one side of a web and being in circumference 25 equal to the length of two pages plus the usual margins, of a single row of printing plates extending around the plate cylinders a distance equal to the length of one page plus the usual margins, a single row of 30 smooth ink-receiving plates slightly lower than the printing plates extending part way around the plate cylinders, a set of form rollers applying ink to the single row of printing plates and the single row of smooth 35 ink-receiving plates on the plate cylinders, a second set of form rollers adapted to take up ink from the single set of smooth ink receiving plates carried by the same plate cylinders, means for raising and lowering said 40 form rollers individually to ink the stereotype plate and the slightly lower smooth surface plates, and means for inking the first set of form rollers.

2. In a rotary web-perfecting machine, 45 the combination of plate cylinders each adapted to perfect one side of a web and being equipped with a single row of printing plates extending around the plate cylinders a distance equal to the length of one 50 page plus the usual margins, each of said plate cylinders being further equipped with a smooth ink-receiving surface slightly lower than the printing plates and extending part way around the plate cylinder, said printing 55 plates adapted to print on a continuously moving web from a single set of plates laying around the cylinders, the printed pages constituting any one row on the webs being all identical and all printed from the same 60 printing plates with usual margins intervening, a web forwarding device comprising two oppositely revolving cylinders laterally adjustable with respect to each other and adapted to coact to forward the intervening 65 web in advance of the first plate cylinder

and independent of the coaction of plate and impression cylinders, substantially as described.

3. In a printing press, a deck-driving shaft driven by a vertical drive shaft through 70 the medium of bevel gears, a spur gear on the opposite end of said deck-drive shaft adapted to drive stationary plate cylinder driving gears through the medium of intermediate spur gears on each side of the spur 75 gear on the deck drive shaft, and the plate cylinder driving gears positioned to drive movable impression cylinder driving gears, substantially as described.

4. The combination with a plurality of 80 plate cylinders in circumference equal to the length of two plates plus the usual margins, of printing plates extending around the plate cylinders a distance equal to the length 85 of one page plus the usual margins, smooth ink-receiving plates slightly lower than the printing plates extending part way around the plate cylinders, two impression cylinders positioned to coöperate with each plate cylinder for the printing of a continuously 90 moving web, a single ink fountain for each plate cylinder, means for distributing ink from each of said ink fountains to a first set of form rollers, a first set of form rollers applying ink to the printing plates and the 95 smooth ink-receiving plates on the plate cylinders, a second set of form rollers adapted to take up ink from the ink-receiving plates on the plate cylinders and to deposit the ink 100 upon the printing plates carried by the same plate cylinders, means for raising and lowering said form rollers to ink the printing plates and the slightly lower smooth surface plates, and means for equipping each of said 105 plate cylinders with a full complement of 110 impression cylinders whereby one of the impression cylinders in contact with each of the plate cylinders and said second set of form rollers may be thrown out of commission.

5. In a printing press, a deck-driving 110 shaft driven by a vertical drive shaft through the medium of bevel gears, a spur gear on the opposite end of said deck-drive shaft adapted to drive intermeshing gears 115 of spaced apart printing units, and said spur gear slidably keyed to said deck-driving shaft whereby said spur gear may be withdrawn from meshing relation with the gears of spaced apart printing units, substantially as described.

6. In a device of the class described, a multideck frame comprising horizontal frame members upon two sides of the device at each deck, vertical frame members between the horizontal frame members of adjacent decks, said vertical frame members comprising a column or post on each side between said side frame members, plate cylinders having bearings on the horizontal frame members of each deck, said plate 125 130

cylinders being mounted symmetrically upon each side of the columns or posts of a deck and extending above the side frame members, a pair of impression cylinders for each plate cylinder, said impression cylinders having their upper surfaces below the upper surfaces of the plate cylinders, a pair of pulling rolls having bearings mounted on said columns or posts above the plate cylinders, and gears connecting said pulling rolls and said plate cylinders, said impression cylinders being geared to said plate cylinders, but not to each other, and being adjustable with respect to said plate cylinders to permit a plate to be applied to the top of a plate cylinder.

7. The combination of a single plate printing machine comprising a plurality of decks, two plate cylinders and four impression cylinders on each deck, two ink fountains and distributing means and form rollers co-operating with said plate cylinders on each deck, means for leading a web over one of said plate cylinders to one of the inside impression cylinders and around underneath the plate cylinder to the second impression cylinder, means for leading the web back again to another inside impression cylinder and underneath the second plate cylinder to the last impression cylinder.

8. The combination of two plate cylinders, columns lying circumferential to the plate cylinders, impression cylinders having their upper surfaces lying below said plate cylinders, a single row of plates lying the length of one page around each plate cylinder, the plate cylinders and impression cylinders being of a different diameter, two ink fountains on the outside of the plate cylinders, one set of ink distributing means above said impression cylinder and co-operating with said ink fountain, another set of ink distributing means above the other impression cylinder and co-operating with the other ink fountain, means for leading a web over a distributing means and ink fountain to perfect the under side of the web and means for perfecting the reverse side of the web and means for running the web underneath the other distributing means and ink fountains.

9. A printing machine employing a single set of original plates for each four page sheet comprising a multi-deck frame having horizontal frame members for each deck separated by and supported by vertical frame members between decks, said vertical frame members comprising a central supporting column upon each side of the frame, means for supporting a paper roll at the rear of each deck, a plate cylinder and two impression cylinders co-operating with the plate cylinder lying between the central column and said paper roll, a second plate

cylinder and two impression cylinders co-operating therewith lying upon the other side of said central columns, said plate cylinders having bearings supported in the horizontal frame members of said deck, said impression cylinders having bearings in said horizontal frame members, said bearings being placed to permit the top of the plate cylinders to be above the impression cylinders, to permit ready change of plates on said plate cylinders, both of said plate cylinders lying in substantially the same horizontal plane and all of the impression cylinders lying in substantially the same horizontal plane for a single deck, the printing plates on said plate cylinders having a single row of pages lying around the circumference of the plate cylinders for perfecting the web.

10. A printing machine employing a single set of original plates for each four page sheet comprising a frame having horizontal frame members upon two sides of the machine, at each deck, vertical frame members between the horizontal frame members of adjacent decks, said vertical frame members comprising a column or post on each side between said side frame members, plate cylinders having bearings on the horizontal frame members of each deck, said plate cylinders being mounted symmetrically upon each side of the column or posts of a deck and extending above the side frame members, a pair of impression cylinders for each plate cylinder, said impression cylinders having their upper surfaces below the upper surfaces of the plate cylinders, said impression cylinders being adjustable relative to the co-operating plate cylinders, an ink-fountain and distributing means for the first plate cylinder running below the run of the incoming web and another ink-fountain and distributing means lying above the perfected web, the plates on said plate cylinders having a single row of pages lying around the circumference of the plate cylinders for perfecting the web.

11. A printing machine employing a single set of original plates for each four page sheet adapted to perfect on both sides a plurality of continuously moving webs comprising two plate cylinders and four impression cylinders on each deck, said plate cylinders having their upper surfaces on a higher level than said impression cylinders, ink-fountains, one lying between the roll of paper and the first plate cylinder and another lying beyond the second plate cylinder in the direction of the run of the web, and ink distributing means between said plate cylinders and said ink-fountains, said plate cylinders being equipped with a single row of printing plates lying the length of one page around the plate cylinder.

12. The combination of a plate cylinder, a plurality of pages in width and equipped with a single row of printing plates lying the length of one page around the plate cylinder, two impression cylinders on a lower level than said plate cylinder, the plate cylinder being so positioned as to put the printing matter on top of said plate cylinder and above said impression cylinder, 5 form rollers and distributing means above one of said impression cylinders, and a single ink-fountain for said cylinder co-operating with said distributing means, and another set of form rollers underneath said 10 plate cylinder, the printing plates lying in a straight line axially on a part of the circumferential surface of the cylinder and a smooth surface lying in a straight line on the rest of the circumferential surface. 15
13. A printing machine employing a single set of original plates for each four page sheet having printing cylinders, a plurality of pages in width having a single row of plates lying in a straight line with columns lying circumferential of the plate cylinders, impression cylinders co-operating with each of the plate cylinders, said plate cylinders being on a higher level than said impression cylinders, and ink distributing 20 means for each plate cylinder, also being on a higher level than said impression cylinders and a single ink-fountain co-operating with each of said plate cylinders, means for perfecting the under side of a web first on 25 one plate cylinder, means for thereafter perfecting the reverse side of the web in a straight line on the other plate cylinder. 30
14. In combination, a plate cylinder of a circumference twice the length of a page, 35 a printing plate lying part way around said circumference, two impression cylinders co-operating with the plate cylinder, means for leading the web between the plate cylinder and the first impression cylinder and 40 means for leading the web between the plate cylinder and the second impression cylinder for perfecting one side of the web before printing the other side, said latter means comprising means for maintaining the 45 length of web between the first point of impression and the second point of impression substantially equal to the length of two pages or a multiple thereof said printing 50 cylinder and said impression cylinders having their axes lying on substantially the 55 same horizontal line. 60
15. In combination, a plate cylinder of a circumference twice the length of a page, a printing plate lying part way around said circumference, two impression cylinders co-operating with the plate cylinder, means for leading the web between the plate cylinder and the first impression cylinder and means 65 for leading the web between the plate cylinder and the second impression cylinder for perfecting the web on one side before printing on the other, said last means comprising means for maintaining a length of web between the first point of impression and the second point of impression substantially 70 equal to the length of two pages plus margins only, one of said pages being blank and the other being printed, said second means comprising a plurality of adjustable 75 guide rollers, said printing cylinder and said impression cylinders having their axes lying on substantially the same horizontal line. 80
16. In combination, a plate cylinder of a circumference twice the length of a page, a printing plate lying part way around said circumference, two impression cylinders co-operating with the plate cylinder, means for leading the web between the plate cylinder and the first impression cylinder, means 85 for leading the web between the plate cylinder and the second impression cylinder, said latter means comprising means for maintaining a length of web between the first point of impression and the second point of impression substantially equal to the 90 length of two pages, one of said pages being blank and the other being printed, said second means comprising a pair of adjustable guide rollers lying underneath the plate cylinder, said rollers being spaced from the plate cylinder and from each other to provide a space between the web connecting them and the adjacent face of the plate cylinder to provide room for form rollers, 95 said rollers being spaced apart from each other a greater distance than the diameter of the plate cylinder to cause the web to hug the impression cylinders. 100
17. In combination, a plate cylinder of a circumference twice the length of a page, a printing plate lying part way around said circumference, two impression cylinders co-operating with the plate cylinder, means for leading the web between the plate cylinder and the first impression cylinder, means for 105 leading the web between the plate cylinder and the second impression cylinder, and means for maintaining a length of web between the first point of impression and the second point of impression substantially 110 equal to the length of two pages, one or said pages being blank and the other being printed, said second means comprising a 115 pair of adjustable guide rollers, said rollers being spaced from the plate cylinder and from each other to provide a space between the web connecting them and the adjacent face of the plate cylinder to provide room for form rollers, and form rollers for transferring ink from the smooth inking surface 120 on the plate cylinder and depositing it upon 125

the printing plate, said adjustable guide rollers being spaced apart from each other a greater distance than the diameter of the plate cylinder to cause the web to hug the 5 impression cylinders.

18. In combination, a plate cylinder of a circumference twice the length of a plate, a printing plate lying part way around said circumference, two impression cylinders co-
10 operating with the plate cylinder, means for leading the web between the plate cylinder and the first impression cylinder, means for leading the web between the plate cylinder and the second impression cylinder for per-
15 fecting the lower side of the web before printing the other side, said latter means comprising means for maintaining a length of web between the first point of impression and the second point of impression substan-
20 tially equal to the length of two pages, and a second plate cylinder having two coöperating impression cylinders for perfecting the other side of the web, and means for leading the web from the first plate cylinder to the 25 second plate cylinder to bring the first side of the web in contact with the second plate cylinder, said last means comprising an adjustable guide roller for bringing the web in register on the second plate cylinder, said
30 printing cylinder and said impression cylinder having their axes lying on substantially the same horizontal plane, the impression cylinders between the two plate cylinders being spaced apart to permit of independent
35 adjustment of said impression cylinders with respect to their coöperating plate cylinders.
19. In combination, a plate cylinder of a circumference twice the length of a page, a printing plate lying part way around said 40 circumference, two impression cylinders co-
operating with the plate cylinder, means for leading the web between the plate cylinder and the first impression cylinder, means for leading the web between the plate cylinder and the second impression cylinder, for per-
45 fecting the lower side of the web before printing on the upper side said latter means comprising means for maintaining a length of web between the first point of impression and the second point of impression substan-
50 tially equal to the length of two pages, said second and said third means comprising adjustable guide rollers, a second plate cylinder having two coöperating impression cylinders for perfecting the other side of the web, said web being led over the first plate cylinder to the first impression cylinder and being led from the second impression cylinder under the first plate cylinder and its
55 impression cylinder to the second plate cylinder to print on the other side of the web.
20. In combination, a printing surface with a single row of pages lying in a straight line with columns in the direction of the

printing surface, two impression cylinders 65 coöperating with the printing surface, means for leading the web over the printing surface and between the printing surface and the first impression cylinder to print pages separated by blank spaces the length of one 70 page on the lower side of the web, means to lead the web between the printing surface and the second impression cylinder to print the blank space, means for inking the printing surface before reaching the first im- 75 pression cylinder, and means for inking the printing surface before reaching the second impression cylinder, both of said means operating from one ink fountain, said im-
pression cylinders lying on substantially the 80 same horizontal line, said ink fountains ly-
ing above and on the outer sides of the plate cylinders.

21. In combination, a plate cylinder, a pair of impression cylinders having their 85 axes lying on substantially the same level as the axis of the plate cylinder, and a pair of adjustable guide rollers spaced apart laterally below the plate cylinder and adapted to maintain a length of web substan-
90 tially equal to the length of two pages plus margins between the first and second impres-
sions on the plate cylinder.

22. The combination of a printing ma-
chine employing a single set of original 95 plates for each four page sheet comprising four impression cylinders and coöperating plate cylinders in tandem on the same level, plate cylinders adapted to be equipped with original plates comprising a two page print-
ing surface or a four page printing surface, said plate cylinders extending above said impression cylinders to permit of facile application of the plates and feeding mechanisms in such relations to the plate cylinders 100 as to permit the printing of a four page sheet or two four page sheets from a single set of original plates for each four page sheet.

23. The combination of a printing ma-
chine employing a single set of original plates for each four page sheet with col-
umns lying circumferential to the plate cylinders comprising four impression cylinders and coöperating plate cylinders in tandem 115 on the same level, the plate cylinders adapted to be equipped with original plates comprising a two page printing surface or a four page printing surface, said plate cylinders being on a higher level than said im-
pression cylinders, and feeding mechanism in such relation to the plate cylinders as to permit the printing of a four page sheet or two four page sheets from a single set of original plates for each four page sheet.

24. The combination of a printing ma-
chine employing a single set of original plates for each four page sheet with col-

- umns lying circumferential to the plate cylinders comprising four impression cylinders and coöperating plate cylinders on one horizontal plane on the same level and four impression cylinders and plate cylinders on a different horizontal plane on the same level, said plate cylinders being on a higher level than said impression cylinders and being adapted to be equipped with original plates comprising a two page printing surface or a four page printing surface, feeding mechanism in such relation to the plate cylinders as to permit the printing of one, or two, or three four page sheets from a single set of original plates for each four page sheet.
25. The combination of a printing machine employing a single set of original plates for each four page sheet; columns lying circumferential to plate cylinders, comprising a main framework, four impression cylinders lying in a straight line on said framework, plate cylinders on a higher level than said impression cylinders, said plate and impression cylinders being of a different size in circumference, ink distributing means also being on a higher level than said impression cylinders, and a former and rotary folder coöperating with said printing machine.
30. 26. The combination of a printing machine employing a single set of original plates for each four page sheet; columns lying circumferential to plate cylinders, comprising a main framework, four impression cylinders lying in a straight line on said framework, plate cylinders on a higher level than said impression cylinders, said impression cylinders being of a different size in circumference, ink distributing means also being on a higher level than said impression cylinders, a framework on a higher horizontal plane than said first named framework, and four impression cylinders lying in a straight line on said latter framework on a different horizontal plane from said first impression cylinder, and plate cylinders on a different level than said last named impression cylinders, ink distributing means being on a higher level than said last named impression cylinders and a former and rotary folder coöperating with said printing machine.
27. In combination, a deck frame having horizontal side members and vertical posts intermediate the end of the side members, a pair of plate cylinders mounted on said side members one on each side of the vertical posts, coöperating impression cylinders for the plate cylinders lying on each side of the posts and being spaced apart and independent of each other, a pair of pulling rolls mounted on said vertical posts for forwarding the web at the same surface speed as the plate cylinders and a common central drive member located adjacent the posts and lying between the plate cylinders and having driving connection with said pulling rolls and with said plate cylinders.
28. In combination, a plate cylinder two pages in circumference having a plurality of printing plates lying in a straight line the length of one page around the cylinder and an ink distributing surface lying the rest of the way around the cylinder, a pair of impression cylinders half the circumference of the printing cylinder, means between said impression cylinders, for maintaining a length of web equal to two pages plus margins between the impression cylinders, said plate cylinder being driven in such a direction as to move the web downwardly toward the first impression, a single overshot ink fountain lying on the opposite side of the plate cylinder from the first impression cylinder, the side of the plate cylinder adjacent the ink fountain moving upwardly.
29. In combination, a plate cylinder two pages in circumference having a plurality of printing plates lying in a straight line the length of one page around the cylinder and an ink distributing surface lying the rest of the way around the cylinder a pair of impression cylinders half the circumference of the printing cylinder, means between said impression cylinders for maintaining a length of web equal to two pages plus margins between impression cylinders, said plate cylinder being driven in such a direction as to move the web downwardly for the first impression, a single overshot ink fountain lying on the opposite side of the plate cylinder from the first impression cylinder, the side of the plate cylinder adjacent the ink fountain moving upwardly, inking rollers adjacent to the upper portion of the plate cylinder for applying ink to the plate cylinders and a plurality of inking rollers for taking ink from the ink distributing surface and applying it to the printing surface on the cylinder, means for raising and lowering said inking rollers individually and ink distributing mechanism adjacent the upper inking rollers.
30. The combination of a printing machine employing a single set of original plates for each four page sheet, comprising one plate cylinder and two coöperating impression cylinders, a plurality of printing plates lying in a straight line on said plate cylinder part way around the circumference of said plate cylinder, the other part of said plate cylinder being used as an inking device, the printing cylinder being driven in such a direction as to move the web downwardly for the first impression, a single overshot ink fountain coöperating with said plate cylinder and lying on the

side of the plate cylinder opposite the first impression cylinder, and ink distributing means and two sets of form rollers, and means for raising and lowering the form rollers individually.

31. The combination of a printing machine employing a single set of original plates for each four page sheet comprising one plate cylinder and two coöperating impression cylinders, said plate cylinder being on a higher level than said impression cylinders, a plurality of printing plates lying in a straight line on said plate cylinder part way around the circumference of said plate cylinder, the other part of said plate cylinder being used as an inking device, the plate cylinder being driven in such a direction as to move the web downwardly for the first impression, a single overshot ink fountain coöperating with said plate cylinder and lying on the side of the plate cylinder opposite the first impression cylinder, and ink distributing means and two sets of form rollers and means for raising and lowering the form rollers individually.

32. The combination of a single plate printing machine comprising two plate cylinders and four impression cylinders lying in a straight line, said plate cylinders being on a higher level than impression cylinders, and two sets of ink distributing means also being on a higher level than the impression cylinders, and two ink fountains coöperating with said distributing means, a single row of printing plates lying in a straight line on plate cylinders and part way around the circumference of said plate cylinders, the other part of said plate cylinders being used as inking devices, two sets of form rollers coöperating with each plate cylinder, two adjustable rollers below said plate cylinders, form rollers underneath said plate cylinders and between said adjustable rollers, said adjustable rollers being adapted to leave the right margins between the pages on one side of the web, second adjustable means between the first and second plate cylinder and adapted to register the pages on the reverse side of the web.

33. The combination of a printing machine employing a single set of original plates for each four page sheet comprising two plate cylinders and coöperating impression cylinders, columns lying circumferential to the plate cylinders, said plate cylinders being on a higher level than said impression cylinders, a single row of plates lying the length of the page around each plate cylinder, the impression surface being twice the area of the printing surface, two ink fountains, one coöperating with each plate cylinder, one set of ink distributing means coöperating with each plate cylinder, means for leading a web over a distributing means and ink fountain to one plate cylinder

to print the underside of the web and means including the second printing cylinder for perfecting the reverse side of the web and means for running the web underneath the other distributing means and ink fountain.

34. In combination, a horizontal deck frame, a plurality of plate cylinders and four coöperating impression cylinders, the plate cylinders extending above the impression cylinders, the impression cylinders lying on the same horizontal plane in said frame and being spaced apart and means comprising sliding boxes for the impression cylinders for adjusting the impression cylinders with respect to the plate cylinders, the plate cylinders having stationary boxes.

35. In combination, a horizontal deck frame, a pair of plate cylinders having bearings in said frame, a vertical post member lying between said bearings, impression cylinders for said plate cylinders also having bearings in said deck frame, said impression cylinders comprising two impression cylinders one coöperating with each plate cylinder, said two impression cylinders lying on opposite side of the post and being spaced apart to permit of independent adjustment of each of said two impression cylinders with respect to the coöperating plate cylinders, said two impression cylinders being driven independently of each other, a common driving element, a pair of gears driven by said common driving element, each gear having a driving connection to one of said plate cylinders, said plate cylinders extending above the impression cylinders to permit of facile application of the printing plates.

36. In combination, a horizontal deck frame, a pair of plate cylinders having bearings in said frame, a vertical post member lying between said bearing, impression cylinders for said plate cylinders also having bearings in said deck frame, said impression cylinders comprising two impression cylinders, one coöperating with each plate cylinder, said two impression cylinders lying on opposite sides of the post and being spaced apart to permit of independent adjustment of each of said two impression cylinders with respect to the coöperating plate cylinders, said two impression cylinders being driven independently of each other, a common driving element, a pair of gears driven by said common driving element, each gear having a driving connection to one of said plate cylinders.

37. In combination, a horizontal deck frame, a pair of plate cylinders having bearings in said frame, a vertical post member lying between said bearing, impression cylinders for said plate cylinders also having bearings in said deck frame, said impression cylinders comprising two impression cylinders, one coöperating with each plate cylinder,

der said two impression cylinders lying on opposite sides of the post and being spaced apart to permit of independent adjustment of each of said two impression cylinders 5 with respect to the coöperating plate cylinders, said two impression cylinders being driven independently of each other, said plate cylinders extending above the impression cylinders to permit of facile application 10 of the printing plates, said two impression cylinders being driven independently of each other by their respective plate cylinders, a common driving element, a pair of gears meshing with each other, each gear 15 being connected to the adjacent plate cylinder.

38. In combination of a pair of printing couples, each comprising a plate cylinder and impression cylinder means, said plate 20 cylinders each extending above the coöperating impression cylinder means for ease in applying printing plates, said impression cylinder means having twice the area of the printing plate area of the coöperating plate 25 cylinder, means for leading the web to the first couple over the first couple to print the under side of the web, means for leading the web printed on one side up between the two couples to the second couple to perfect 30 the top side of the web, one ink fountain for each plate cylinder lying at opposite sides of both plate cylinders.

39. In combination, a pair of printing couples lying on the same deck for perfecting a web, each printing couple comprising a plate cylinder having a plate thereon of substantially the length of one page in circumference and two impression cylinders coöperating with each plate cylinder, said 40 impression cylinders of each couple coöperating with the corresponding plate cylinder at such points as to leave ample room at the top of the plate cylinders for the application of the plates, means for leading the web 45 over the first printing couple before it reaches the first impression cylinder of the first couple and means for leading the web printed on one side under the first printing couple to an impression cylinder of the second printing couple, and two ink fountains 50 lying at opposite ends of the companion printing couples.

40. In combination, a plate cylinder substantially equal to two pages in circumference, a printing plate of substantially the 55 length of one page, a pair of impression cylinders for said plate cylinder, a pair of adjustable guide rollers of small diameter below the plate cylinder adapted to maintain a length of web equal to the length of two pages plus margins between the first and the second impression cylinder and providing a 60 space for inking mechanism, inking mechanism in said space, said adjustable rollers lying outside the point of contact of the im-

pression cylinders and the plate cylinders to increase the length of contact of the web on the impression cylinders and to provide ample room for said inking mechanism.

41. In combination, a plate cylinder of a 70 circumference substantially equal to two pages, a printing plate of substantially the length of one page on said cylinder, a pair of impression cylinders each of a diameter substantially half the diameter of the plate 75 cylinder, a pair of adjustable rollers of small diameter below said plate cylinder adapted to maintain a length of web equal to the length of two pages plus margins between the first and second impression cylinders, 80 said adjustable rollers being spaced apart a greater distance than the diameter of the plate cylinders so that the length of contact of the web and the impression cylinders is increased.

42. In combination, a plate cylinder of a circumference substantially equal to two pages, a printing plate of substantially the length of one page on said cylinder, a pair of impression cylinders each of a diameter 90 substantially half the diameter of the plate cylinder, a pair of adjustable rollers of small diameter below said plate cylinder adapted to maintain a length of web equal 95 to the length of two pages plus margins between the first and second impression cylinders, said adjustable rollers being spaced apart a greater distance than the diameter of the plate cylinders so that the length of contact of the web and the impression cylinders is increased and means for leading the web over said plate cylinder to the first impression cylinder and means for leading the web printed on one side under the plate cylinder from the second impression cylinder. 100

43. In combination, a pair of printing couples on the same deck, each printing couple comprising means for printing one side of the web, comprising a plate cylinder 110 and an impression cylinder, means for leading the web to the first couple over said first couple, means for leading the web printed on the side from the first couple to the second couple, said means including an adjusting device for taking up the desired length of web between the first and second plate cylinders, said couples being spaced apart and said web printed on one side passing up between the printing couples from the first 115 couple to the second couple, said couples comprising printing plates one page in length with the plates lying in a straight line and extending above the impression cylinders for the facile application of the 120 plates, said impression cylinders having twice the circumferential area of the plate cylinders.

44. In combination a pair of printing couples lying on the same deck, each com- 125

- prising a plate cylinder and a coöperating impression cylinder, means for leading the web to one of the printing couples over the first couple, adjustable means between the 5 first couple and the second couple for adjusting the length of web between them so that the margins will not simultaneously strike the web whereby a continuous pull on the web is maintained.
- 10 45. The combination of a printing machine comprising two impression cylinders and a coöperating printing surface printing pages lying in a straight line a plurality of pages in width, and lying the length of one 15 page on said printing surface, said columns of the pages lying in the same direction as the rotation of the impression cylinders, means for printing the underside of a web on the first impression cylinder and print- 20 ing surface and means for passing the web around two adjustable rollers to leave a space for said inking rollers, and means for perfecting the same side of the web on the second impression cylinder and same print-

ing surfaces with the usual margin between 25 the pages.

46. The combination of a pair of printing couples, each comprising a plate cylinder having a single row of printing plates lying in a straight line, a plurality of pages in 30 width, columns lying circumferential to the plate cylinders, each plate cylinder extending above the coöperating impression cylinder means, for ease in applying printing plates, impression cylinder means having 35 twice the area of the printing plate area of the coöperating plate cylinder, means for leading the web to the first couple to perfect 40 the reverse side of the web, and means for leading the web to the second couple to perfect the reverse side of the web, one ink fountain for each plate cylinder lying at opposite sides of both plate cylinders.
